US0D1110067S

(12) **United States Design Patent** (10) **Patent No.:** **US D1,110,067 S**
(45) **Date of Patent:** **** Jan. 27, 2026**

(54) **PILLOW**

(71) Applicant: **Shenzhen Xindezhong Electronic Technology Co., Ltd.**, Shenzhen (CN)

(72) Inventor: **Shuying Hu**, Shenzhen (CN)

(73) Assignee: **Shenzhen Xindezhong Electronic Technology Co., Ltd.**, Shenzhen (CN)

(**) Term: **15 Years**

(21) Appl. No.: **29/862,502**

(22) Filed: **Dec. 9, 2022**

(30) **Foreign Application Priority Data**

Jun. 10, 2022 (CN) 202230353357.3

(51) **LOC (15) Cl.** **06-09**

(52) **U.S. Cl.**

USPC **D6/604**; D6/601

(58) **Field of Classification Search**

USPC D6/595, 596, 597, 598, 601, 604

CPC A47G 9/00; A47G 9/10; A47G 9/1009;

A47G 9/1027; A47G 9/1054; A47G

9/1072; A47G 9/1081; A47G 9/109;

A47G 2009/1018

(57) **CLAIM**

The ornamental design for a pillow, as shown and described.

DESCRIPTION

FIG. 1 is a rear perspective view of a pillow, showing my new design;

FIG. 2 is a front perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the pillow, which form no part of the claimed design.

1 Claim, 8 Drawing Sheets
